United States Patent

Des. 240,120
Patented June 1, 1976

240,120

COMBUSTION PRODUCTS DETECTOR

Ralph E. Pasquarette, Jordan, Minn., assignor to
Honeywell Inc., Minneapolis, Minn.

Filed Nov. 21, 1974, Ser. No. 525,784

Term of patent 14 years

Int. Cl. D10—05

U.S. Cl. D10—106

FIG. 1

FIG. 2

FIG. 3

FIG. 1 is a top plan view of a combustion products detector showing my new design;

FIG. 2 is a typical side elevational view thereof; and

FIG. 3 is a top perspective view thereof.

The recessed base shown by FIGS. 2 and 3 is generally flat and rectangular with mitered corners.

I claim:

The ornamental design for a combustion products detector, substantially as shown and described.
